METHOD AND APPARATUS FOR CLEANING
CARPETS

Charles D. Marekres, Des Moines, Iowa

Application October 12, 1933, Serial No. 693,293

4 Claims. (Cl. 15—104)

The objects of my invention are to provide a carpet cleaner of simple, durable and inexpensive construction, which may be readily, quickly and easily moved by an operator backwardly and forwardly over a carpet, and when so moved, with relatively slight downward pressure, will remove from the carpet light dust, grains of sand or the like embedded in the carpet nap, and fibrous material such as hair, wool or the like resting upon the top of the nap, and retain all of these materials within the cleaner, and without permitting any of the lighter dust particles thus removed from the carpet to escape into the air; and

Further to provide a carpet cleaner of this class in which the materials thus separated from the carpet and retained within the cleaner may be readily, quickly and easily removed from the cleaner by simply immersing in a suitable liquid.

A further object is to provide an improved method for cleaning carpets, which method consists in depressing the nap of the carpet and bringing to the surface of the carpet materials to be removed therefrom, and then employing the resiliency of the carpet nap to throw the materials thus removed from the carpet upwardly and catching and holding said materials and fine dust thus removed from the carpet, and finally removing such materials from the cleaner, readily, quickly and easily without permitting the escape into the air of the fine dust thus removed.

My invention consists in the construction, arrangement and combination of the various parts of my improved cleaner, and in the method of removing dust and other materials from the carpet, whereby the objects contemplated are attained, as hereinafter more fully set forth, pointed out in my claims, and illustrated in the accompanying drawing, in which:

Figure 1 shows a top or plan view of my improved cleaner.

Figure 2 shows a central, longitudinal, sectional view of same.

Figure 3 shows an end elevation of same; and

Figure 4 shows an enlarged, detail, sectional view illustrating my improved method of removing foreign materials from a carpet.

Referring to the accompanying drawing, it will be seen that my improved cleaner comprises a frame consisting of two side plates 10 having 50 pivotally connected therewith two rods 11, which are extended upwardly and toward each other and have a ferrule 12 at their upper ends to which a handle 13 is fixed.

Between these side plates 10 there is a series 55 of transversely arranged bars, each of which

comprises a body portion 14 having a longitudinal groove 15 on its under surface and two flat bottom edges 16 on its under surface, the outer edges of which are relatively sharp at 17 and from this sharp edge there is an inclined surface 18 extending upwardly and toward the longitudinal center of the bar, and between this inclined surface 18 and the body of the bar there is a longitudinally arranged pocket 19. These bars stand spaced apart from each other, as clearly shown in Figure 2, and are rigidly fixed in the side frames. Preferably the outer edges of the two outer bars are inclined upwardly at 20.

In practical use with my improved carpet cleaner, I proceed as follows: I first provide a receptacle in which there is contained a liquid, which may be composed of one part gasoline and ten parts water. I then dip the cleaner in this solution and the surfaces of the bars are made of such material that a thin layer of this liquid solution 20 will adhere thereto.

I then press the cleaner slightly downwardly into the carpet and rapidly move the cleaner backwardly and forwardly over the carpet to be cleaned. While this is being done, the relatively sharp advance edges of the bars will press the nap of the carpet downwardly and in the direction in which the cleaner is being pushed. Hence, these sharp edges will penetrate into the carpet almost down to the body of the carpet into which the nap is woven. This will cause material such for instance as grains of sand to be scraped toward the outer ends of the nap. It will also cause such materials as small wool fibers, hair and so forth to be scraped and rolled into small, 30 loosely united rolls, and then as the bar proceeds over the carpet, the nap springs back to upright position as soon as a bar has passed over, and this upward springing movement of the nap throws the material removed from the carpet upwardly and rearwardly relative to the line of advance, and causes this material to be received 40 into the pocket of the next following bar. So far as the fine light dust particles are concerned, these are also thrown upwardly and adhere to the liquid layer on the bars, and substantially none of this fine dust reaches the atmosphere above the cleaner.

In regard to the longitudinal groove 15, I have repeatedly demonstrated in practice that a very 50 substantial quantity of the finer particles of dust are thrown up into this groove by the nap and caused to adhere to the cleaner within the central portion of the groove. Then when a relatively small area of carpet has thus been gone over, 55

the operator dips the cleaner into the vessel containing the said liquid, and all of the dust and other material contained therein is instantly deposited within said liquid and a new layer 5 of dust retaining liquid is thereby applied to the cleaner.

My improved method of carpet cleaning is as follows: I first spread a thin layer of liquid of a character to which dust, etc. will readily adhere, 10 over the entire surface of the cleaner. Illustrated in Figure 4 at A. I have had satisfactory results in practice in this feature of my invention by forming the bars of clear soft pine wood and dipping the cleaner in a solution of ten parts water 15 and one part gasoline. The wood causes the layer of liquid to adhere to it for a sufficient length of time, and the liquid mixture causes the dust, etc. to adhere to the liquid coated surfaces which do not come in direct contact with the carpet.

20 I then move the cleaner over a carpet, and press downwardly on the cleaner, thus causing the sharp advance edges of the bars to press the nap of the carpet downwardly and along the line of advance of the cleaner, as illustrated in Figure 25 4. As these bars successively pass over a given area of carpet, these advance sharp edges scrape particles of sand, crumbs, etc. to the surface of the carpet. At the same time they cause particles of wool, threads, hairs, etc. to form into loosely connected rolls on the surface of the carpet.

Then after one bar passes over a given area of the carpet, the nap of the carpet is released and springs upwardly, thus throwing said materials on the surface of the carpet upwardly beyond the sharp edge of the adjacent approaching bar. Also the raising movement of the nap after being released by one bar carries the said materials thereon up high enough so that the approaching sharp edge of the following bar will 35 pass under it, and said materials will be forced into the pockets and against the liquid coated surfaces of the bar above the parts which are in engagement with the carpet. The function of the layer of liquid is to cause said materials, including fine dust, to adhere to said surfaces and not rise upwardly beyond the bars or be shaken off to return to the floor.

40 After a short period of use, the cleaner is dipped in a vessel containing said liquid, which performs

the double function of removing all of the material deposited upon the cleaner and supply a new liquid layer. The arrow in Figure 4 shows the direction in which the cleaner is advancing over the carpet.

5

I claim as my invention:

1. A carpet cleaner comprising a frame, a handle secured to the frame, a series of bars arranged substantially parallel with each other slightly spaced apart and having their lower surfaces projected below the frame, the lower side edges of the bars being inclined upwardly and toward the longitudinal center of the bar, and adapted to have a coating of liquid applied to the bars for dust collecting purposes. 10

2. A carpet cleaner comprising a frame, a handle secured to the frame, a series of bars arranged substantially parallel with each other slightly spaced apart and having their lower surfaces projected below the frame, the lower side edges of the bars being inclined upwardly and toward the longitudinal center of the bar, and adapted to have a coating of liquid applied to the bars for dust collecting purposes, the sides of the bars being formed with pockets extending longitudinally 20 of the bars for collecting heavier particles. 25

3. A carpet cleaner comprising a frame, a handle secured to the frame, a series of bars arranged substantially parallel with each other slightly spaced apart and having their lower surfaces projected below the frame, the lower side edges of the bars being inclined upwardly and toward the longitudinal center of the bar, and adapted to have a coating of liquid applied to the bars for dust collecting purposes, the bottom surface of 30 each bar being formed with a longitudinally arranged groove for the purposes stated. 35

4. A carpet cleaner comprising a frame, a handle secured to the frame, a series of bars arranged substantially parallel with each other slightly spaced apart and having their lower surfaces projected below the frame, the lower side edges of the bars being inclined upwardly and toward the longitudinal center of the bar, and adapted to have a coating of liquid applied to the bars for 40 dust collecting purposes, said bars being made of soft wood to which a layer of water or other liquid will adhere. 45

CHARLES D. MARCKRES.
